GRINDING MILL

Donald J. Brown, 3426 Fairesta, La Crescenta, Calif.

Filed Aug. 10, 1965, Ser. No. 86,520

Term of patent 14 years

(Cl. D37—1)

FIG. 1 is a side elevational view of one side of a grinding mill showing my new design;

FIG. 2 is a side elevational view of an opposite side thereof;

FIG. 3 is a front elevational view;

FIG. 4 is a back elevational view; and

FIG. 5 is a top plan view of the same.

The dominant features of my design reside in the portions shown in full lines.

I claim:

The ornamental design for a grinding mill, substantially as shown and described.
